UNITED STATES PATENT OFFICE.

BERTRAND G. JAMIESON, OF CHICAGO, ILLINOIS.

TELEPHONE SYSTEM.

1,096,108.

Specification of Letters Patent.

Patented May 12, 1914.

Application filed August 15, 1911. Serial No. 644,174.

To all whom it may concern:

Be it known that I, BERTRAND G. JAMIESON, a citizen of the United States, residing at Chicago, in the county of Cook and State of Illinois, have invented a certain new and useful Improvement in Telephone Systems, of which the following is a full, clear, concise, and exact description, reference being had to the accompanying drawings, forming 10 a part of this specification.

My invention relates to telephone systems and has for its object the provision of means whereby certain signaling indications may be established at the central exchange 15 at the will of the subscriber.

My invention is of particular utility for private branch exchange switchboards, although not so limited.

In this description and drawing, I show 20 and describe my invention as applied to a common battery telephone system, although it will be understood it is not to be so limited. It is customary in common battery systems, for instance, for a signal to be 25 operated at the exchange in response to the actuation of the switchboard lever at the substation.

My invention concerns itself with the provision of means whereby the operator may 30 receive a further signaling indication which notifies the operator that the subscriber is temporarily away from his instrument and which signaling indication may be discontinued when the subscriber returns so that 35 he is again accessible through the instrument.

In the form herein shown my invention concerns itself with providing the operator 40 with an audible signal which she receives upon making the test and which audible signal informs her that the line she desires while not busy, is not available for calling purposes as the subscriber for that line is away from the instrument.

I will explain my invention more in detail, by reference to the accompanying drawing illustrating one embodiment thereof diagrammatically.

In the drawing I have illustrated a central exchange A and two substations B and C served by this exchange. The substation B has the customary receiver 1, switchhook lever 2, induction coil 3, condenser 4, transmitter 5, signal receiving device 6 and condenser 7 all associated with the line wires 8 and 9. The equipment is similar at the

substation C. The lines 8 and 9 at the central exchange are associated with the line relay 10, cut off relay 11, common battery 12, answering jack 13, answering lamp 14 and multiple jacks 15. The thimbles 16 of the jacks are connected together by means of the conductor 17 as is well understood and this conductor is associated with a cut off relay 11, the other terminal of said cut off relay being grounded. This line circuit arrangement and also the cord circuit arrangement is of well known construction and is not part of my invention. The cord circuit has the customary plugs 18 and 19, 70 the talking strands 20 and 21, and the supervisory and telephone circuit controlling strand 22. The cord circuit is likewise provided with the ordinary repeating coils 23, 23, supervisory lamps 24, 24, listening keys 75 25 and an operator's set 26.

Whenever the switchhook is moved to close the line circuit at the substation, the answering lamp 14 is actuated by the line relay 10 to be extinguished thereafter by the 80 cut off relay 11. At the substation I further provide a switch consisting of a spring 27, a contact 28, resistance 29 and button 30 which I utilize for sending a selective signal to the central station to apprise the operator 85 when attempting to connect with this line, that said line is not available as the subscriber is temporarily away from his instrument. When the relay 10 receives its full energizing current as when the switchhook 90 lever 2 is in its raised position, then the armatures 31 and 32 are attracted to light the lamp 14 and also to perform another function that will presently appear. Should however a less amount of current be supplied to the relay 10 as when the button 30 is actuated to close the circuit across the conductors 8 and 9 through the resistance 27, then this current is not sufficient to actuate the armatures 32 and 33, but sufficient to 100 actuate the armature 31, which armature 31 therefore is in closed circuit with its contact 35, and by means of the conductor 36 passing through the condenser 37, connects the conductor 17 through said armature 31, contact 35, conductor 38, contact 39, conductor 40, with the secondary winding 41 of a vibrator 42. The other terminal of the conductor 41 is then grounded.

It will thus be seen that while the button 110 30 is depressed the thimbles 16 are connected to ground through the secondary winding 41.

This secondary winding 41 is in inductive relation with a primary winding 43, which primary winding is continually impressing impulses inductively on the secondary winding 41, as the said primary winding is associated through battery 34 with a vibratory contact 45. Now should the operator in making a test, as when the substation B is desired, connect the tip 46 of her answering plug with a thimble 16, then a circuit is established from ground 47 through the secondary winding 41, conductor 40, intermediate contacts 39 and 35, condenser 37, conductor 17, thimbles 16, tip 46, conductor 48, repeating coil 23 to ground at 49. The operator thus hears the buzzing emitted by the vibrator 42 and knows that the line desired is not available as the subscriber is away from the instrument temporarily. Time is thus saved in calling this station or attempting to call this station to ascertain if the party desired is there. Now when the plug 18 is inserted in the jack however in order to make an emergency call for station B, then the armatures of relay 10 are restored nevertheless by virtue of the energizing of the relay 11 so that the vibrator 42 is disconnected from the thimble 16. When the subscriber returns he releases the button 30 and his line is again available for use. The switchhook 2 is provided with a depending arm 50 so that when the said switchhook is to place the line in service, this depending arm 50 releases the button 30 and thereby opens the bridge including the resistance 29. It will thus be seen that not only the answering but the multiple jacks are provided with means whereby the subscriber may establish distinctive conditions so that the operator 40 will be apprised of the availability of the line when she desires to make a call. A great deal of time can thus be saved. The push button 30 may also be under direct control of some other instrumentality that actuates manually, and this is illustrated at substation C where the push button 30^a is under the control of the sliding top 51 of a roll top desk, the table top of which is indicated at 52.

50 As before stated I am showing the invention specifically here in connection with a common battery system and also describe specifically merely one embodiment of the many which my invention may take. I do not limit myself therefore to this specific description, but having thus described one embodiment of my invention,

What I claim as new and desire to secure by Letters Patent is:

60 1. A telephone system having a central exchange, a plurality of substations, and circuits uniting said substations with said central exchange, connecting terminals for each line circuit at the exchange, a common switchboard for said circuits and connecting terminals, means

65

terminals, means under the control of the substation for establishing at the said switchboard the "busy" and "not busy" condition of its associated line, and means controlled at the substation for establishing at the said switchboard a further and at will permanent distinctive thimble test condition of its associated line.

2. A telephone system having a central exchange, a plurality of substations, and circuits uniting said substations with said central exchange, a common switchboard for said circuits, means under the control of the substation for establishing at the said switchboard the "busy" and "not busy" condition of its associated line, and means controlled at the substation for establishing at the said switchboard a further and at will permanent distinctive thimble test condition of its associated line whereby to convey to the same operator distinctive signaling indications.

3. A telephone system having a central exchange, a plurality of substations, and circuits uniting said substations with said central exchange, connecting terminals including test thimbles for each line circuit at the exchange, means under the control of the substation for establishing at the exchange the "busy" and "not busy" condition of its associated line, and means controlled at the substation for establishing at the exchange in connection with said test thimbles a further distinctive condition of its associated line.

4. A telephone system having a central exchange, a plurality of substations, and circuits uniting said substations with said central exchange, connecting terminals including multiple test thimbles for each line circuit at the exchange, means under the control of the substation for establishing at the exchange the "busy" and "not busy" condition of its associated line, and means controlled at the substation for establishing at the exchange in connection with said multiple test thimbles a further distinctive condition of its associated line.

5. A telephone system having a central exchange, a plurality of substations, and circuits uniting said substations with said central exchange, a common switchboard for said circuits and connecting terminals, means under the control of the substation for establishing at the said switchboard the "busy" and "not busy" condition of its associated line, means controlled at the substation for establishing at the said switchboard, a further and at will permanent distinctive thimble test condition of its associated line, and means whereby the last aforesaid means is controlled by the first aforesaid means.

6. A telephone system having a central exchange, a plurality of substations, and circuits uniting said substations with said cen-

tral exchange, a common switchboard for
said circuits and connecting terminals,
means under the control of the substation
for establishing at the exchange the "busy"
5 and "not busy" condition of its associated
line, and means controlled at the substation
for establishing at the said switchboard a
further and at will permanent distinctive
10 thimble test condition of its associated line,
said last aforesaid means including a switch
and an impedance device.

7. A telephone system having a central
exchange, a plurality of substations, and cir-
cuits uniting said substations with said cen-
tral exchange, a common switchboard for
15 said circuits and connecting terminals,
means under the control of the substation

for establishing at the exchange the "busy"
and "not busy" condition of its associated
line, and means controlled at the substation 20
for establishing at the said switchboard a
further and at will permanent distinctive
thimble test condition of its associated line,
said last aforesaid means including a switch
25 and an impedance device, said impedance de-
vice having sufficient impedance not to in-
juriously affect the talking condition of the
line.

In witness whereof, I hereunto subscribe
my name this 3rd day of August A. D., 1911. 30

BERTRAND G. JAMIESON.
